6 Claims. — (Cl. 103—2)

1

My invention has for its object a pump adapted to transmit substantially equal pressures to different liquids, one of which is a lubricant and the other may be a liquid fuel intended for the feeding of an internal combustion motor. According to a primary feature of said invention, this pump is constituted by one or more cylinders inside each of which may slide two pistons arranged in series and secured to one another with a certain longitudinal play; the first piston acts on the lubricant which transmits its pressure to the second piston which acts in its turn on the fuel; the arrangement forms thus two elementary pumps, one for the fuel and one for the lubricant which ensures thus a permanent lubrication of the pump and its auxiliary mechanisms at a pressure which is in constant equilibrium with that of the fuel.

According to a further feature of the invention, the pressure chamber of the fuel pump is provided with a by-pass including a freely sliding piston adapted to set the inlet in direct communication with the outlet, said freely sliding piston remaining in equilibrium between the pressure of the fuel on one side thereof and that of the lubricant acting on the other side under the influence of a suitable regulator.

In the case of a multicylinder pump, the different cylinders may be arranged in parallelism round the control shaft, the pistons being simultaneously actuated as well known in the art by means of a plate arranged obliquely with reference to said control shaft and the rotation of which produces the reciprocation of the pistons.

This pump is particularly suitable for feeding internal combustion motors of any kind, whether of the gasoline explosion, heavy fuel Diesel or any other type, by means of the device described and claimed in my copending application filed May 18, 1945, Serial No. 594,484, now abandoned, under the title "Method and device for feeding fuel to internal combustion motors." In case of this combination with last mentioned device, my present invention may be associated with a rotary fuel distributor for which it provides both lubrication and equilibrium in operation, as well as for the other parts of the equipment, perfect fluid tightness as concerns the fuel being simultaneously ensured by means of a slight overpressure of lubricant.

When feeding an internal combustion motor and more particularly a motor of the gasoline explosion type, the pump may be used without a fuel distributor, said fuel being in such a case fed directly to the injectors under permanent pressure and the distribution being effected in ac-

2

cordance with the desired cycle through suitable mechanical, hydraulic, electric or the like control means while the lubricant is forced directly into the common injector lubricating pipe.

5 I have described hereinafter an embodiment of my invention, given by way of example, and illustrated in accompanying drawings.

Fig. 1 is a vertical cross-section of a five cylinder pump according to the invention, adapted to feed an internal combustion motor and associated with a fuel distributor for the motor cylinders.

Fig. 2 is a horizontal cross-section through line II—II of Fig. 1.

Fig. 3 is a horizontal cross-section through line III—III of Fig. 1.

Fig. 4 is a horizontal cross-section through line IV—IV of Fig. 1.

Fig. 5 is a cross-section of part of the pump through line V—V of Fig. 4.

20 Fig. 6 is a cross-section of another part of the pump through line VI—VI of Fig. 4.

Fig. 7 is a detail cross-sectional view through line VII—VII of Fig. 1.

Referring to said drawings showing by way of example a pump including five parallel cylinders, it is apparent that said pump is constituted by the assembly of three casings to wit: a casing 1 containing the control mechanisms, a casing 2 containing the elementary pumps and the casing 3 containing the fuel distributor.

These casings are connected through their flanges such as 4 and 5 rigidly secured to the adjacent casing by means of annularly distributed bolts, studs or the like.

35 The casing 1 is provided with a flange 6 for mounting the pump assembly on the motor. The pump is driven through the shaft 7 rotatably carried in the bush 8. Said shaft 7 is provided with an oblique bearing 9 which carries a loose gearwheel 11 through the agency of a needle bearing or the like part. This gearwheel 11 is provided with toothed sectors in constant engagement with the teeth of another gearwheel 12 which is stationary and rigid with the casing 1.

40 The gearwheel 11 cannot rotate, but the bent shaft 7 as it rotates causes it to assume a tacking motion through the agency of the bearing 13. This motion is transmitted simultaneously to each of the five pistons 14 adapted to slide in the corresponding cylinders 15 arranged in parallelism with the axis of the pump and distributed at equal intervals round same. These pistons are thus urged into a reciprocating motion due to the fact that the extensions 16 of the gearwheel 11 45 act on the connecting rods 17 of the pistons

through the balls 18 cooperating with the pistons 14 and the springs 20 to hold said extensions 16 in operative connection with said connecting rods.

In its reciprocating motion, each of the pistons 14 drives, through a tenon 22 engaging a mortise 23, the piston 21 which slides in the same cylinder 15. The two pistons 14 and 21 are assembled with some play and between them is provided a chamber 24 the volume of which therefore vary and which constitutes an elementary oil pump.

The entrance of oil into the pump 24 is effected through a port 25 (Fig. 6) provided in the flange of the pump in front of a port provided in the casing of the motor and fed with oil under pressure by the lubricating circuit of the motor. This oil enters the chamber closed by a plug 26 and passes through a filter 27 inside the general casing of the pump after lifting a ball valve 28 which serves to prevent the pump from becoming empty when it ceases running.

The oil enters then a groove 29 ensures the lubrication of the bush 8 and passes into the central channel 30 bored along the axis of the pump shaft 7. To the end of this shaft is secured, by means of a key 31 and a hollow screw 32, a sleeve 33 centrally fitted inside the bush 34 integral with or rigidly secured to the stationary gearwheel 12. The reaction produced in the shaft 7 by the motion of the gearwheel 11 is absorbed by the ball thrust bearing 35. The sleeve 33 rotating with the shaft drives through a screwdriver connection 36 the oil feed distributor 37. Said distributor rotates inside a bearing 38 rigid with the casing 2 and provided axially with an oil feed channel 39 opening in front of the central channel 30 of the pumpshaft 7. The oil passes from said aligned channels 38 and 39 into the channel 40 leading to the abovementioned chamber 24 of the elementary oil pump. The oil distributor comprises moreover at its outer periphery, a narrow annular chamber 41 the lower part 41a of which extends only over part of a circumference as shown in cross-section in Fig. 7.

It is apparent that, as it rotates, the distributor causes the channels 40 of the different cylinders to communicate in turn, first with the oil feed channel 39 and then with the part annular chamber portion 41a. Through the associated movements of the pistons and of the distributor, the oil is sucked through the channels 38 and 39 into the different pistons in succession, out of which they are forced into the circular chamber 41. From this chamber, the oil under pressure is led through the channel 42 into the fuel distributor 43 of which it ensures the lubrication and moreover, through the channel 44, towards the regulator of which it controls the operation, as will be disclosed hereinafter.

Furthermore, as the pistons 21 are provided with a reciprocating motion, there is a consequent variation in volume of the chambers 45 which form the elementary fuel pumps. The fuel enters said pumps under a certain pressure through the connection 46 (Fig. 3), the filters 47-48 and the annular chamber 49 in which the fuel is collected for suction into the chambers 45. It enters the latter through the groove 50 and the ports 51 uncovered only when the piston 21 is at the end of its suction stroke. During the return stroke, the fuel is forced through the flap valve 52 into the annular chamber 53 forming the delivery collecting chamber and from said space into the filter 54 and the fuel distributor 43. The delivery 75 motor through pipes secured to connections such

collecting chamber or duct 53 may communicate with the suction collecting chamber 49 through a by-pass system including a piston 55 adapted to move freely in either direction inside a cylinder 56 under the action respectively of the fuel pressure in the collecting chamber 53 and of the oil pressure in the chamber 51. The freely moving piston 55 covers and uncovers during its displacements a suitably shaped port 58 which allows the temporary return flow of part of the fuel which is delivered back into the suction collecting chamber 49. The oil pressure in the chamber 51 and consequently that of the fuel in the collecting chamber 53 is determined by the equilibrium of the slide valve 59 subjected on one side to the oil pressure in the channel 44 and on the other to the action of a set of levers 60-61 adapted to transmit the variable force exerted by the pressure regulator.

The slide valve 59, as it moves, uncovers either the oil inlet ports 62 or the oil escape ports 63 inside the casing 1 whereby it adjusts the oil pressure in the chamber 51 through the channel 44. A calibrated diaphragm 65 prevents any jerks 25 from occurring in the transmission of said pressure to the freely sliding piston 55.

The pressure regulator (Figs. 1 and 4) comprises chiefly a yielding diaphragm 66 held tightly between two flanges 67 and 68 inside a recess provided between a wall of the casing 1 and a cover 69 secured to said main casing through an annular series of bolts or studs.

The large diameter diaphragm 66 separates the recess into two chambers 70 and 71 which may 35 communicate through the connections 72 and 73 (Fig. 4) with two different sources of pressure. If one uses only one source of pressure connected for instance with the chamber 70, the chamber 71 is subjected to the circumambient pressure 40 through a port provided in the wall of the casing.

The diaphragm 66 is moreover subjected to the action of a spring 74 adjustable from the outside through the screw 75 and a sliding nut 76 acting on said spring.

45 The diaphragm 66 acts through a central boss 77 on the lever 61 (Fig. 1) with the interposition of a ball 78.

A small yielding diaphragm 79 is arranged so as to 50 separate the chamber 71 from the inside of the casing 1 without preventing the central boss 77 from acting on the ball 78.

The crank lever 61 (Fig. 1) rotates round its axis and transmits to the lever 60 the pressure it receives from the ball 78 with the interposition 55 of the ball 80 located inside the cage 81 forming part of the lever 82 (Fig. 4) pivotally secured to the spindle 83. This lever 82 may be moved from outside the casing by means of a micrometric screw 84 including an inner set screw 85 for holding the lever 82 in the desired position by fastening the cover 86.

The pump which has been described by way of example is particularly adapted to provide the feeding of a motor through direct atomising of 65 the fuel into the cylinders and it is associated with means for distributing the fuel towards the different cylinders of the motor.

These distributing means are contained in the casing 3 and comprise chiefly a rotor 87 (Figs. 1 and 2) rotatively driven by the oil distributor 37 through the screw driver connection 37-a. The inside of the rotor communicates through a channel 88 with the fuel delivery collecting chamber 53. The fuel is led towards the cylinders of the 70 motor through pipes secured to connections such

as 89 the number of which is equal to that of the cylinders and which may be arranged for instance in two rows. Openings 90 and 91 are provided in the rotor for communication with the connections 92-93 from which the pipes leading to the cylinders start. The size and direction of these openings are such as will provide for the feeding of each cylinder at the moment and during the time required by the distribution used for the motor.

The rotor 87 rotates inside the bearing 94. Lubricating grooves 95 and 96 are provided between the rows or tiers of connections 89 and are fed with oil under pressure through the channel 97 communicating with the delivery of the oil pumps through the chamber 98.

As the inside of the pump casing should be at circumambient pressure, a channel 99 (Fig. 1) is provided in the flange 6, for removing the excess oil towards the casing of the motor. For certain positions of the pump, in particular when it is upside down with the flange 6 uppermost, the channel 99 can no longer fulfil this part and there may be provided a pump for exhausting the oil, as is shown in Fig. 5. This pump includes a cylinder 100 containing a piston 101 the suction stroke of which is ensured by a spring 102 and the delivery stroke by a push member 103 controlled by the movable gearwheel and adapted to slide in the bearing 104 rigid with the stationary gearwheel 12. The oil is sucked through the ports 105 and is forced through the flap valve 106 into a pipe secured to the connection 107.

To remove all risks of the pump being locked in case of the piston 101 being seized inside the cylinder 100, an elastic mounting is provided between the push member 103 and the piston 101, said mounting being constituted by a step 108 urged by a spring 109 against a stop formed by an annulus 110. Of course the spring 109 is strong enough to constantly make the step bear against its stop during normal operation and it is compressed only when the friction between the piston 101 and its cylinder 100 becomes exaggerated.

The working of the pump arrangement described is as follows: As it rotates, the shaft 7 gives the movable gearwheel 11 a tacking motion which communicates a reciprocating motion to all the pairs of cooperating pistons 14-21, which pistons are connected so as to provide between them a variable volume chamber 24. The oil distributor 37 is keyed to the shaft 7 in a manner such that the channel 39 comes opposite the channel 40 at the moment when the piston 14 begins its downward stroke. As the oil is forced under pressure from the motor through the channels 25, 29, 30 and 40, it fills immediately the chambers 24 between the cooperating pistons.

During the same time, the piston 21 produces in the chamber 45 a depression which becomes apparent at the end of the suction stroke in the groove 50, whereby the fuel is sucked in from the chamber 49 and the fuel container through the connection 46.

Thus the pistons 14 and 21 execute simultaneously their suction stroke.

During the next or delivery stroke, the piston 21 forces the fuel out of the chamber 45 which raises the flap valve 52 in the chamber 53 for a predetermined pressure P . The fuel is then led through the pipe 88 towards the distributor and thence through the ports 90 and 91 into the connections 89 communicating through suitable pipes with the motor cylinder.

The ports 90 and 91 of the distributor are arranged and the distributor is set with reference to the shaft 7 in a manner such that the admission of fuel is effected in each cylinder with the timing and for the duration required by the distribution in the motor.

While the pistons 14 and 21 execute their delivery stroke, the oil in the chamber 24 is automatically set under the pressure of the fuel in the chamber 45, which pressure may be designated by $P+p$, P being the pressure of delivery into the collecting chamber 53 and p the loss of head produced by the flap valve 52 in accordance with the compression of the return spring of this flap valve. The loss of head which may be ascribed to the movement of the piston 21 may be considered as negligible. The oil forms thus in the chamber a cushion opposing the leaks of fuel while at the same time ensuring the lubrication of the piston 21.

At the same time the oil is forced through the channels 42, 98 and 97 into the fuel distributor which is thus subjected on one side to the pressure of the fuel arriving inside the rotor under a pressure P and on the other to the pressure $P+p$ of the oil entering the chamber 98. These two pressures are very near in value as p may be small. This difference in pressure p causes the distributor to bear against the stop in its bearing. In practice the distributor is balanced whatever may be the value of P , which value may be comparatively high.

Moreover the fuel cannot escape towards the chamber 98 as the excess pressure p of the oil would prevent such an escape. This oil pressure is also exerted in the grooves 95 and 96, which ensures perfect lubrication of the rotor and prevents any communication between the different distribution circuits.

As to the operation of the regulating means, it is apparent from Figs. 1 and 4 that if a differential air pressure is exerted between the connections 72 and 73 on either side of the diaphragm 66, the latter will be subjected to a deformation, which through the leverage 60-61 produces a displacement of the slide valve 59. The spring 74 allows a constant adjustable pressure to be added to the action of the air pressure. Moreover it is possible to act through the lever 82 and the screw 84 on the lever arms of the leverage and consequently vary the ratio between the movements of the central boss 77 on the diaphragm 66 and those of the slide valve 59. The slide valve 59 receives therefore an upwardly directed impulse of a predetermined adjustable value in direct relationship to the differential air pressure appearing between the connections 72 and 73.

The oil arriving through the channel 44 at the pressure $P+p$ mentioned hereinabove, passes through the ports 62 and enters the channel 64 in the slide valve 59 and the chamber 57. Under the action of the oil pressure, the slide valve 59 moves downwardly until the pressure produced by the regulator as disclosed hereinabove, which pressure is exerted upwardly, balances the pressure exerted in the downward direction by the oil on the upper surface of the piston, the ports 62 being then covered.

If the differential air pressure modifying the pressure exerted by the regulator is reduced, the slide valve 59 moves further down and begins uncovering the channel 63, which allows a certain amount of oil under pressure to escape and to return to the pumps. There prevails thus con-

stantly in the chamber 51 a well defined oil pressure corresponding to the differential air pressure acting on the regulator diaphragm.

Now this oil pressure exerts also in the chamber 51 a pressure on the lower end of the freely sliding piston 55 the other end of which is subjected to the pressure P of the fuel delivered by the pumps. The oil pressure in the chamber 51 is thus equal to the pressure P of the fuel in the chamber 53. The two pressures balance one another and hold the piston 55 in a position such that the port 58 is partly covered, exactly in accordance with the output required.

If for any reason whatever, an overpressure arises in the fuel delivery collecting chamber 53, the freely sliding piston 55 moves and uncovers to a greater extent the port 58 whereby a greater amount of fuel is allowed to return into the suction collecting chamber 48 and the output is reduced.

If, on the contrary, the pressure decreases in the fuel delivery collecting chamber 53, the freely sliding piston 55 rises under the action of the oil pressure and covers to a greater extent the by-pass port 58 whereby the output of fuel increases and equilibrium is restored between the two opposed pressures.

The chamber 51 and the slide valve 59 form a small auxiliary motor the operation of which is ensured by the excess pressure p of the oil pressure upstream with reference to the motor. As disclosed hereinabove the excess pressure p depends solely on the pressure exerted by the return springs of the flap valves 52.

This excess pressure p is entirely independent of the operating pressure of the pump, which may be very high. By suitably choosing the value of this pressure p and by reason of the small inertia of the freely sliding piston 55, it is possible to obtain practically instantaneous regulating movements together with an extremely high sensitivity of the regulator described.

The working of the oil exhaust pump illustrated in Fig. 5 is obvious. The movable gearwheel 11, in its tacking motion, constantly urges the push member 103 into reciprocation so that said member slides in its bearing 104 and displaces the piston 101 in its cylinder 100. When the oil arrives inside the casing in front of the ports 105, it enters the cylinder and at each delivery stroke, is forced through the flap valve 106 into a pipe communicating with the connection 107 and adapted to return it into the motor casing.

We have described a pump of the barrel type comprising five double cylinders mounted in parallel but obviously any other number of cylinders may be chosen. On the other hand, it is apparent that the description hereinabove must not be construed in a limiting sense and that the scope of the invention, as defined by the accompanying claims, is far wider and covers in particular multi-cylinder pumps the pistons of which are in alignment or arranged in V or star relationship and are controlled in any known or suitable manner.

Also it has been assumed that the motor is fed through a distributor associated with the pump, but the feeding of the motor might as well be effected directly, by means of injectors controlled through a camshaft or else through any suitable hydraulic, electrical or the like means. In this case, the pump is provided with an oil delivery duct and with a fuel delivery duct connected respectively with the injector lubricating collecting chamber and with the common injector feeding pipe.

It is apparent that my improved pump allows the simultaneous delivery of a non-lubricant liquid at a predetermined pressure and the lubrication of all moving parts by means of oil held under a pressure at least equal to that of the fuel so as to prevent any leaking of the latter, these cooperating pressures being constantly in equilibrium and held at a predetermined value by a regulator subjected to a variable or constant outer pressure.

What I claim is:

1. A pump for feeding simultaneously fuel and lubricant to an internal combustion motor comprising at least one cylinder, two pistons adapted to reciprocate in each cylinder, means for interconnecting the pistons in each cylinder with a longitudinal play between them; means for supplying fuel and lubricant to the cylinders, means for driving the first piston in each cylinder, means whereby said first piston forces the lubricant out of the corresponding cylinder, means whereby said first piston drives the corresponding second piston through the interposed lubricant pressure, means whereby the second piston in each cylinder delivers the fuel into the motor and means whereby the lubricant forced out of each cylinder by the first piston lubricates the pump parts at a pressure which constantly balances that of the fuel.

2. A pump for feeding simultaneously fuel and lubricant to an internal combustion motor comprising an annular series of parallel cylinders, two aligned pistons adapted to reciprocate in each cylinder, means for interconnecting the pistons in each cylinder with a longitudinal play between them, fuel and lubricant supply means, a plate oblique with reference to the axes of the cylinders, means for making said plate rotate round an axis parallel to the cylinder axes means whereby said plate controls the reciprocation of the first piston in each cylinder, means whereby said first piston forces the lubricant out of the cylinder, means whereby said first piston drives the corresponding second piston through the interposed lubricant pressure means whereby the second piston in each cylinder delivers the fuel into the motor and means whereby the lubricant forced out of each cylinder by the first piston lubricates the pump parts at a pressure which constantly balances that of the fuel.

3. In a pump as claimed in claim 1 the provision of a fuel collecting chamber between the second piston and the means whereby the second piston delivers fuel to the motor, a by-pass for said chamber communicating with the fuel supply and with the outlet of the collecting chamber and including a freely sliding piston adapted to control the passage through the by-pass between the fuel supply and the outlet of the collecting chamber, means whereby the lubricant pressure acts on the freely sliding piston and a regulator controlling the pressure of the lubricant.

4. In a pump as claimed in claim 1 the provision of a fuel collecting chamber between the second piston and the means whereby the second piston delivers fuel to the motor, a by-pass for said chamber communicating with the fuel supply and with the outlet of the collecting chamber and including a freely sliding piston adapted to control the passage through the by-pass between the fuel supply and the outlet of the collecting chamber, means whereby the lubricant pressure acts on the freely sliding piston, and a regulator controlling the pressure of the lubricant including a diaphragm subjected at least on one side to air

pressure, a set of levers operatively related to said diaphragm, a slide valve subjected to the action of the lubricant pressure and operatively related with the other end of said set of levers, and means whereby the displacements of the slide valve control the passage of lubricant to the freely sliding piston whereby the lubricant pressure and consequently the fuel pressure are determined by the air pressure acting on the diaphragm.

5. In a pump as claimed in claim 1 the provision of a fuel collecting chamber between the second piston and the means whereby the second piston delivers fuel to the motor, a by-pass for said chamber communicating with the fuel supply and with the outlet of the collecting chamber and including a freely sliding piston adapted to control the passage through the by-pass between the fuel supply and the outlet of the collecting chamber, means whereby the lubricant pressure acts on the freely sliding piston, and a regulator controlling the pressure of the lubricant including a diaphragm subjected at least on one side to air pressure, a set of levers operatively related at one end to said diaphragm, adjustable elastic means adapted to exert a constant pressure on the diaphragm in addition to the air pressure, a slide valve subjected to the action of the lubricant pres-

sure and operatively related to the other end of said set of levers, and means whereby the displacements of the slide valve control the passage of lubricant to the freely sliding piston whereby the lubricant pressure and consequently the fuel pressure are determined by the air pressure acting on the diaphragm.

6. In a pump as claimed in claim 1, the provision of a rotary distributor, means for driving said distributor, means whereby the distributor is fed with fuel by the fuel delivery means and means whereby the distributor is lubricated by the lubricant from the pump cylinders at a pressure slightly above that of the fuel.
